UNITED STATES PATENT OFFICE.

AUGUST SCHOEN, OF PHILADELPHIA, PENNSYLVANIA, ASSIGNOR TO SAMUEL B. STINSON, ROBERT J. STINSON, JOSEPH C. STINSON, AND THOMAS STINSON, OF SAME PLACE, TRADING AS STINSON BROS.

MOVABLE SWIFT FOR COP-WINDING MACHINES.

SPECIFICATION forming part of Letters Patent No. 683,806, dated October 1, 1901.

Application filed June 25, 1900. Serial No. 21,398. (No model.)

To all whom it may concern:

Be it known that I, AUGUST SCHOEN, a citizen of the United States, residing at the city of Philadelphia, in the county of Philadelphia and State of Pennsylvania, have invented certain new and useful Improvements in Cop-Winding Machines, of which the following is a specification.

My invention has relation to a machine for winding yarn or thread onto shuttle-cops.

The principal object of my invention is to provide a machine with a spindle carrying a spool or cop, means for rotating the spindle, a support having tension rods or guides, a weighted bracket provided with eyes through which the yarn or thread passes, and a riser for laying the thread or yarn uniformly onto each spool or cop, in combination with a standard forked at its upper end to form back-stops, an arm pivoted in the forked portions of the standard and carrying at its opposite end a reel or swift adapted to be shifted into operative position, with its carrying-arm contacting with one of the back-stops, and in a similar manner into inoperative position, with its carrying-arm brought into contact with the other of the back-stops for either removing the reel or swift from its carrying-arm or winding a fresh supply of yarn or thread onto the same.

My invention consists of a cop-winding machine constructed and arranged in substantially the manner hereinafter described and claimed.

The nature, characteristic features, and scope of my invention will be more fully understood from the following description, taken in connection with the accompanying drawings, forming part hereof, in which—

Figure 1 is a front elevational view of a cop-winding machine embodying characteristic features of my invention. Fig. 2 is a side elevational view showing the movable swift in its normal or operative position for use with the thread or yarn drawn therefrom onto the cop and also showing in dotted outline the movable swift in an inoperative position for receiving a fresh supply of yarn. Fig. 3 is a front elevational view, partly in broken section, of the support or standard with the mov-

able arms of adjacent swifts arranged in pairs in connection with the support or standard for permitting of the shifting of the swifts from their operative into inoperative position to permit of the removal or replacing of yarn on the same and returning to their operative position without disturbing companion or adjoining swifts arranged in series in the machine. Fig. 4 is a side elevational view of the two arms with their supports or standards, showing a portion of the framework of the cop-winding machine and the said two arms, respectively, in positions in which the swifts in connection therewith will occupy, respectively, operative and inoperative positions in connection with the machine. Fig. 5 is a view, partly in side elevation and partly in section, of the several members constituting my present invention for maintaining the yarn or thread under tension in its passage or travel from the swift or reel to the bobbin or cop. Fig. 6 is an enlarged detail view in elevation of the weighted tension bracket or arm of the machine, and Fig. 7 is a transverse sectional view on the line xx of Fig. 6.

Referring to the drawings, A represents a cop-winding machine provided with a main operating-shaft a , carrying pulleys a' , which are connected by a belt a^2 with a grooved pulley b , mounted on a vertical spindle b' and carrying at the upper end a spool b^2 to become a shuttle-cop, these cops being, as shown, arranged in series in the machine, as is well understood.

c is a series of vertical supports or standards secured to the top of the framework of the machine A, near the outer edge, in any suitable manner and provided with back-stops c' and c^2 for a purpose to be presently described. To each of these supports or standards c are pivotally secured, preferably, two curvilinear arms d and d' , adapted to be shifted or swung both in the same direction or in opposite directions to each other and provided at their upper ends with journals d^2 and d^3 , adapted each to receive a yarn reel or swift e of the type illustrated in Figs. 1 and 2, whereby the swift in operative condition is held in a vertically-central position above the machine A. In the operative and inoperative

positions of the arms d and d' they are supported or held by the back-stops c' and c^2 of the standard c , which also limit the ranges of movement respectively of the said arms carrying the reels or swifts.

f is a vertical support or arm secured to the front of the machine A, and at the upper end of each support or arm is located and carried a longitudinal tension-rod f' . This rod f' has 10 fixed thereto a link f^3 , which carries a second longitudinal tension-rod f^2 .

Extending from the front of the machine, beneath the cop or bobbin b^2 , is a bracket G, provided with a weight g and with two eyes 15 g' and g^2 . This bracket G is pivoted to the framework of the machine, as at g^6 , and its downward movement is limited by a stop g^6 , which impinges upon or against said framework of the machine. Intermediate of the 20 two eyes g and g^2 of the weighted bracket G is arranged the forked end of a fixed arm H, over which the thread T passes in its travel from the eye g' to the eye g^2 , as clearly illustrated in Figs. 6 and 7. The bracket G has 25 also a projection g^7 , under which the thread T passes. The weighted bracket G is thus adapted to maintain the thread or yarn T taut in its passage from the reel or swift to the bobbin or spindle, and thereby causing greater 30 uniformity in the laying up of the yarn or thread on the bobbin for subsequent use.

h is a riser adapted to lay the yarn or thread T uniformly onto the shuttle-spindle b' or bobbin b^2 . The reels or swifts, as illustrated in 35 series in Fig. 2, can be readily and quickly shifted from their normal position, as illustrated in full lines in Fig. 2, and held in their inoperative position, as illustrated in dotted lines in said figure, by one of the back-stops 40 c' and c^2 , thus saving labor and time, as well as maintaining the yarn in a cleanly condition during replacing on the reel or swift and avoidance of breakage of the yarn or 45 threads of companion or adjoining yarn-containing reels or swifts of the machine.

The operation of the machine hereinbefore described is as follows: The yarn being placed on the movable reels or swifts and the reels or swifts then caused to assume the positions illustrated in full lines in Figs. 1 and 2, the 50 yarn or thread is then passed in the operation of the machine after power is applied to the main driving-shaft a, operating the spindles of the shuttle-cops b^2 , over and under the two tension-rod f' and f^2 , then through, respectively, the eyes g' and g^2 of the weighted bracket G, and by the riser h the thread or yarn will be laid uniformly onto the bobbin-spindle b' or bobbin b^2 , according to the condition of the bobbin-spindle b' in and during 55 the operation of the machine.

Having thus described the nature and object of my invention, what I claim as new, and desire to secure by Letters Patent, is—

In a machine of the character described, a 65 spindle carrying a spool or cop, means for rotating the spindle, a support having tension rods or guides, a weighted bracket provided with eyes through which the yarn or thread passes and a riser for laying the thread uniformly onto each spool or cop, in combination with a standard forked at its upper end to form back-stops, an arm pivoted in the forked portions of the standard and carrying at its opposite end a reel or swift adapted to be 70 shifted into operative position with its carrying-arm contacting with one of the back-stops and in a similar manner into inoperative position with its carrying-arm brought into contact with the other of the back-stops for either 75 removing the reel or swift from its carrying-arm or winding a fresh supply of yarn or thread onto the same.

In testimony whereof I have hereunto set my signature in the presence of two subscriv- 80 ing witnesses.

AUGUST SCHOEN.
